UNITED STATES PATENT OFFICE.

JAMES H. MASON, OF DETROIT, MICHIGAN.

SAFETY-DOOR FOR HEATERS.

SPECIFICATION forming part of Letters Patent No. 398,271, dated February 19, 1889.

Application filed May 3, 1888. Serial No. 272,691. (No model.)

To all whom it may concern:

Be it known that I, JAMES H. MASON, of Detroit, in the county of Wayne and State of Michigan, have invented a new and useful 5 Improvement in Safety-Doors for Boilers, of which the following is a specification.

My invention consists in an improved safety-door for boilers, especially applicable to car-heaters, hereinafter fully described and 10 claimed.

The drawing is a perspective showing the upper safety-door and fire-door open and the lower safety-door and ash-pit door closed.

A represents the boiler, which may be of 15 any shape or style of construction.

I represents the stoking-hole, provided with the ordinary swinging fire-door, E.

B B represent vertical guides secured to the boiler, one at each side of the fire-door, 20 and C represents a perpendicular plate of iron, whose ends fit and slide vertically in said guides B.

When the boiler is cylindrical, as illustrated in the drawing, the plate C is made to 25 conform to the shape of the boiler. The plate C has a number of fine perforations therein to permit air to pass through the plate, but are not large enough to let sparks or fire pass out, and is provided with a handle, N, by

30 which it may be raised. The plate C is adjusted to slide downward in the guides B down to a point where it completely covers the door E, and is there prevented from further downward motion by any suitable stop 35 in said guides. I provide an automatic locking device for automatically engaging and holding the plate C in its lowest position when it drops down in front of the door E, which locking device is mounted on a part of 40 the stove or heater, and may be of any kind which will act automatically when said plate is at its lowest point.

The lock shown in the drawing, and which I use, consists of an arrow-head, D, on the 45 lower side of the plate C, and the pivoted

spring-jaws F, pivoted to the boiler below the door E, and constantly pressed together by a spring, G, fastened to the boiler at H. On the descent of the plate C the arrow-head D separates these spring-jaws and is clamped 50 between them.

It is evident that any other automatic locking device may be substituted in place of the one shown.

L represents a plate similar to C, provided 55 with perforations and a handle, M, and a locking device, which plate also slides in the guides B, and when down covers the ash-pit door of the heater.

I am aware that a horizontally-moving 60 plate adapted to cover the ash-pit and fire-doors of a heater has been shown and described in a prior patent; but this differs from my invention in that said plate must be closed by hand after the fire and ash-pit doors 65 are closed, while in my device the safety-plates C and L close by gravity, thus rendering the device automatic.

It is evident that the fire-door E cannot be 65 opened until the plate C is raised, and that 70 the instant the fire-door is closed the plate C falls over it and is locked in position, forming an absolute automatic safety-door.

What I claim as my invention, and desire to 75 secure by Letters Patent, is—

The combination, with a heater having an opening and closing door, of a vertically-sliding plate on the heater, which is supported in its elevated position by the door when the latter is open, and drops down in front of the 80 door whenever the latter is closed, and an automatic locking device for holding the sliding plate in its lowest position when it drops down in front of the closed door, substantially as described.

JAMES H. MASON.
